UNITED STATES PATENT OFFICE.

JAMES CLIFFORD THROOP, OF COLUMBUS, KANSAS.

CUFF-BUTTON.

1,371,131.

Specification of Letters Patent.

Patented Mar. 8, 1921.

Application filed February 19, 1920. Serial No. 359,888.

To all whom it may concern:

Be it known that I, JAMES C. THROOP, a citizen of the United States, residing at Columbus, in the county of Cherokee and State 5 of Kansas, have invented certain new and useful Improvements in Cuff-Buttons; of which the following is a specification, reference being had therein to the accompanying drawing.

10 This invention relates to improvements in cuff buttons, one object of the invention being the provision of a novel form of link cuff button, in which the members are readily insertible and removable from the cuff without disturbing or soiling the same.

15 A further object of this invention is the provision of a novel shank and locking arrangement for link cuff buttons, which permits of the easy insertion and withdrawal of 20 the cuff button and at the same time, without in any way affecting the ornamental appearance or detracting therefrom.

25 A still further object of the invention is the provision of a simple, durable and inexpensive link cuff button, which is thoroughly efficient and practical in use.

In the accompanying drawings:

Figure 1 is a perspective view of the complete button, dotted line showing position 30 thereof in the cuff.

Fig. 2 is a plan view of the female member of the button.

Fig. 3 is a plan view of the male member of the button.

35 Fig. 4 is a cross section taken on line 4—4 of Fig. 2, with the two members assembled.

Referring to the drawings, the numeral 5 designates the female member which carries the ornamental end portion 6, and the shank 40 7, said shank being a hollow elongated member having the angular ends 8 and 9, the end 8 being attached to the button. Formed through the wall intermediate of the ends of the shank is a notch 10, the purpose of which 45 will presently appear. The male member 11 of the button includes the ornamental end 12 with the shank 13, which is provided with the fixed guiding portion 14, the resilient locking terminal 15, having the enlargement

16 intermediate of its end for engagement 50 with the notch of the female member to lock the parts assembled.

It will be observed that the female member is of rectangular shape and thus provides a rectangular receiving socket with a notch in 55 one wall of said socket whereby the guiding portion and spring locking tongue are confined in the rectangular tubular socket and prevented from turning, thus holding the two parts in proper position in the cuff 60 while a proper locking engagement is made between the enlargement 16 and the notch 10.

From the foregoing description, taken in connection with the drawings, it is evident that when assembling this button the female 65 shank is projected through both of the buttons of the cuff on the outside thereof, and that the open end of the shank will readily receive the guiding and locking members of the male shank so that when properly assembled 70 the button will be locked in the button and the cuffs will be held together. By disposing the button at the angle indicated, they can conform to the contour of the cuff and be much neater than when disposed 75 parallel as is the usual custom.

I claim:

The cuff button herein shown and described, consisting of a female member carrying a button disposed at an incline to said 80 member and consisting of a tubular socket having a notch therein, said tubular member being of rectangular form with said notch in one edge thereof, a male member carrying a button disposed at an incline to said button 85 and having a shank formed with a cut out of tapered form to provide a guiding portion and a spring arm, said arm being reduced to provide suitable elasticity and formed with an enlargement on one edge and 90 contiguous to its reduced portion to engage the notch of the female member, said enlargement also forming a finger engaging means to release the male and female members.

95

In testimony whereof I affix my signature.

JAMES CLIFFORD THROOP.
